UNITED STATES PATENT OFFICE.

EDWIN LEE TOMLINSON, OF NORTH BRANCH, MICHIGAN.

MUD-GUARD.

1,355,715.

Specification of Letters Patent.

Patented Oct. 12, 1920.

Application filed March 15, 1920. Serial No. 365,741.

To all whom it may concern:

Be it known that I, EDWIN L. TOMLINSON, a citizen of the United States, and a resident of the city of North Branch, in the county 5 of Lapeer and State of Michigan, have invented a new and Improved Mud-Guard, of which the following is a full, clear, and exact description.

This invention relates to improvements in 10 mud guards, an object of the invention being to provide an improved guard adapted to be used on Ford cars and which acts as a shield to prevent the throw of mud against the radiator by the wheels.

15 A further object is to provide a mud guard secured to the ordinary guards of the car and extending across the front of the car at the lower portion of the radiator.

With these and other objects in view, the 20 invention consists in certain novel features of construction and combinations and arrangements of parts as will be more fully hereinafter described and pointed out in the claims.

25 In the accompanying drawings—

Figure 1 is a view in front elevation illustrating my improved guard in position on a car;

Fig. 2 is a fragmentary perspective view 30 showing one end of the guard secured to the ordinary guard; and

Fig. 3 is a view in section on line 3—3 of Fig. 2.

1 represents an ordinary Ford car having 35 a radiator 2 at its front end and provided with the ordinary mud guards 3, 3, positioned on the wheels 4.

5 represents my improved mud guard which is preferably of sheet metal having a 40 straight intermediate portion 6 located across and at the end of the radiator, and having a notch 7 in its upper edge receiving the starting crank 8. A rearwardly projecting flange 6' is provided on the upper edge of the intermediate portion 6 and is 45 positioned directly under the radiator 2.

Forwardly projecting wings 9 are provided at the ends of the intermediate portion 6 and from the upper edges of these 50 wings 9 guards 10 project and slightly overlap the inner portions 11 of the guards 3 and are secured thereto by bolts 12 and nuts 13 or other approved securing devices.

By providing a car with my improved

guards, the mud from the wheels cannot be 55 thrown against the radiator, as is the case with Ford cars in general use, and the attachment can be manufactured and sold at a reasonably low price and attached by any one of average intelligence, not requiring 60 skilled labor. The attachment can be made from a single blank or may constitute separate pieces secured together, and the guard may be ornamented and strengthened in any 65 approved manner.

It will also be noted that the wings 9 and 70 guards 10 are inclined outwardly from their inner or rear edges to their outer or forward edges, to effectively shield the radiator from the throw of the wheels.

Various slight changes might be made in 75 the general form of the parts described without departing from my invention, and hence I do not limit myself to the precise details set forth, but consider myself at liberty to make such slight changes and alterations as fairly fall within the spirit and scope of the appended claims.

I claim:

1. A mud guard of the character stated, 80 comprising a vertically disposed intermediate portion, wings projecting forwardly from the ends of the intermediate portion, and guards extending upwardly and outwardly from the wings.

2. The combination with an automobile 85 having a radiator and having mud guards located beside the same and extending upwardly and outwardly over the wheels, of a radiator mud guard comprising a vertically disposed intermediate portion located below the forward edge of the radiator, forwardly projecting wings fixed to the intermediate portion, and upwardly and outwardly flaring guards on the wings fixedly secured to 90 said first mentioned guards.

3. The combination with an automobile, 95 having a radiator and having mud guards located beside the same and extending upwardly and outwardly over the wheels of the automobile, of a radiator mud guard comprising a straight portion located against the lower front portion of the radiator, wings projecting forwardly from the ends of the straight portion, and upwardly and outwardly projecting guards on the wings secured to the first mentioned guards.

4. The combination with an automobile,

having a radiator and having mud guards located beside the same and extending upwardly and outwardly over the wheels of the automobile, of a radiator mud guard 5 comprising a straight portion located against the lower front portion of the radiator, wings projecting forwardly from the

ends of the straight portion, and upwardly and outwardly projecting guards on the wings secured to the first mentioned guards, 10 said wings and last mentioned guards inclined outwardly from their inner to their outer ends.

EDWIN LEE TOMLINSON.
